UNITED STATES PATENT OFFICE.

EMERY ALEXANDER HASTEN, OF HIGH POINT, NORTH CAROLINA, ASSIGNOR
OF ONE-THIRD TO R. C. MAXWELL, OF SAME PLACE.

TOBACCO STICK OR HANGER.

SPECIFICATION forming part of Letters Patent No. 470,124, dated March 1, 1892.

Application filed October 15, 1891. Serial No. 408,830. (No model.)

To all whom it may concern:

Be it known that I, EMERY ALEXANDER HASTEN, a citizen of the United States, residing at High Point, in the county of Guilford 5 and State of North Carolina, have invented certain new and useful Improvements in Tobacco Sticks or Hangers; and I do hereby declare the following to be a full, clear, and exact description of the invention, such as will 10 enable others skilled in the art to which it appertains to make and use the same.

My invention relates to an improved stick or hanger for supporting tobacco-leaves while the same are being cured; and its novelty will 15 be fully understood from the following description and claim, when taken in conjunction with the accompanying drawings, in which—

Figure 1 is a plan view of my improved stick 20 or hanger; and Fig. 2 is a side elevation of a series of my improved hangers arranged one above the other, each upon three tier-poles.

Referring by letter to the said drawings, A indicates the stick proper or cross-bar of my 25 improved hanger, which is preferably of rectangular form in cross-section and is supported in practice in a horizontal position upon the ordinary tier-poles or in a suitable frame within the curing-barn.

B indicates the horizontal laterally-extending branches of my improved hanger, which are arranged in pairs at suitable intervals in the length of the stick A and are pitched in a corresponding direction with respect to the 30 longitudinal direction of said stick, by reason of which arrangement it will be seen that the said branches will take up less space at the sides of the stick than branches which extend at right angles thereto, which is an important 35 advantage. The respective pairs of branches, which extend in opposite directions from the stick A in the manner described, are formed from a single piece of wire or the like, which is bent at its middle to form the loop C, which 40 is disposed longitudinally with respect to the stick A and is secured thereto at its ends by

a staple a, and is also secured to said stick adjacent to the point where it merges into the branches B by a staple b, which is disposed at right angles to the staple a.

By the provision of the loop C and the peculiar arrangement of the staples a and b, as described, it will be readily perceived that the branches B will be connected to the stick in a rigid and secure manner and will be effectively prevented from working loose in operation.

From the foregoing description, taken in conjunction with the drawings annexed, it will be seen that I have provided a tobacco-hanger of an exceedingly cheap, simple, and durable construction embodying a peculiar arrangement of parts, whereby, while it is adapted to support as many leaves as the ordinary hanger, it will take up much less space, 60 by reason of which it will be seen that more of my improved hangers may be placed in the same space than the ordinary hangers in which the branches extend at right angles to the stick.

Having thus described my invention, what I claim, and desire to secure by Letters Patent, is—

In a tobacco-hanger substantially as described, the combination, with the stick or cross-bar, of a series of projecting metallic arms each formed from a single piece and extending from opposite sides of the stick, the loop formed integrally at the center and disposed longitudinally with respect to the stick, 75 the staple a, securing the end of said loop to the stick, and the staple b, arranged at right angles to the staple a and securing the loop to the stick at a point adjacent to where said loop merges into the branches, all substantially as and for the purpose set forth.

In testimony whereof I affix my signature in presence of two witnesses.

EMERY ALEXANDER HASTEN.
